UNITED STATES PATENT OFFICE

140,814

DESIGN FOR AN UNDERWATER MASK

Donald F. Eddy, South Gate, Calif., assignor to E-Z Swim Mask Company, South Gate, Calif., a partnership

Application February 13, 1945, Serial No. 117,911

Term of patent 7 years

(Cl. D57—1)

To all whom it may concern:

Be it known that I, Donald F. Eddy, a citizen of the United States, residing at South Gate, in the county of Los Angeles, State of California, have invented a new, original, and ornamental Design for an Underwater Mask, of which the following is a specification, reference being had to the accompanying drawing, forming a part thereof.

Fig. 1 is a plan view of an underwater mask showing my new design;

Fig. 2 is a front elevation thereof; and
Fig. 3 is a partial side elevation thereof.

The head strap shown in full in Fig. 1 has been shown fragmentarily in Fig. 3 and omitted entirely from Fig. 2 for convenience of illustration.

I claim:

The ornamental design for an underwater mask, as shown and described.

DONALD F. EDDY.
